US00D781987S

(12) **United States Design Patent** (10) **Patent No.:** **US D781,987 S**
(45) **Date of Patent:** **** Mar. 21, 2017**

(54) **COMPONENT OF A TRIGGER MECHANISM FOR A FIREARM**

(71) Applicant: **WHG Properties, LLC**, North Wales, PA (US)

(72) Inventor: **William H. Geissele**, Lower Gwynedd, PA (US)

(73) Assignee: **WHG Properties, LLC**, North Wales, PA (US)

(**) Term: **15 Years**

(21) Appl. No.: **29/542,312**

(22) Filed: **Oct. 13, 2015**

CLAIM

The ornamental design for a component of a trigger mechanism for a firearm, as shown and described.

DESCRIPTION

FIG. 1 is an isometric view of a component of a trigger mechanism for a firearm;

FIG. 2 is a front elevation view of the component of a trigger mechanism for a firearm of FIG. 1;

FIG. 3 is a rear elevation view of the component of a trigger mechanism for a firearm of FIG. 1;

FIG. 4 is a right side elevation view of the component of a trigger mechanism for a firearm of FIG. 1;

FIG. 5 is a left side elevation view of the component of a trigger mechanism for a firearm of FIG. 1;

FIG. 6 is a top view of the component of a trigger mechanism for a firearm of FIG. 1; and,

FIG. 7 is a bottom view of the component of a trigger mechanism for a firearm of FIG. 1.

The broken lines in the Figures are for illustrative purposes only and form no part of the claimed design.
